Primary Examiner — Austin Murphy(74) *Attorney, Agent, or Firm* — Stephen R. Valancius(57) **CLAIM**

The ornamental design for a grinder, as shown and described.

DESCRIPTION

FIG. 1 is a perspective view of a grinder showing our new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom plan view thereof.

In the above drawings, the broken lines and the areas within the broken lines form no part of the claimed design.

1 Claim, 7 Drawing Sheets(56)
